SWING-DOOR CONTROL MECHANISM

Robert G. Polson, Stockton, Calif., assignor of
one-third to J. Myron Carr, Stockton, Calif.

Application September 3, 1946, Serial No. 694,512

1 Claim. (Cl. 16—182)

1

This invention is directed to, and it is an object to provide, a swing-door control mechanism; said mechanism being operative to normally maintain the door closed by spring means, but permitting the door to be swung to open position in either direction and automatically but releasably latched in said position.

A further object of the invention is to provide a swing-door control mechanism which is neat in appearance and easy to install, and does not require the cutting out of a corner section of the door, as is necessary with conventional devices for the purpose.

Another object of the invention is to provide a swing-door control mechanism which is positive, smooth, and noiseless in operation; the structure being simple but rugged and thus not subject to becoming out of order.

A further object of the invention is to provide a practical swing-door control mechanism, and one which will be effective for the purpose for which it is designed.

These objects are accomplished by means of such structure and relative arrangement of parts as will fully appear by a perusal of the following specification and claim.

In the drawings:

Fig. 1 is an elevation of a door mounted by means of the improved swing-door control mechanism.

Fig. 2 is an enlarged plan view of the mechanism with the base plate removed.

Fig. 3 is a cross section on line 3—3 of Fig. 2.

Referring now more particularly to the characters of reference on the drawings, the swing door control mechanism is here shown as mounted between the floor 1 and the lower inner corner 2 of a swing door 3.

Below the corner 2 of the door 3 the floor is recessed or socketed, as at 4, and the mechanism depends mainly in said socket and comprises the following:

A rectangular base plate 5 is seated on the floor 1 of the socket 4, being secured to the floor by screws which pass through holes 6 in the corners of said base plate.

A rigid case 7 is fixed to the under side of the base plate 5 by screws 8, and depends into the floor socket 4.

A horizontal rotary crosshead 9 is disposed in the case 7, and includes an upwardly projecting spindle 10 which extends in turnable and guided or journalled relation through the base plate 5. Above the base plate 5 the spindle 10 is formed

2

with an upper end portion 11 of non-circular configuration, here square. Said non-circular upper end portion 11 of the spindle removably seats in a matching hole of a bearing plate 12 countersunk in the lower edge of the door at the corner 2. It will thus be seen that upon swinging of the door in one direction or the other from a normally closed position, corresponding rotary motion will be imparted to the crosshead 9 within the case 7.

A thrust washer 13 surrounds the spindle portion 11 between the bearing plate 12 and the top of the base plate 5, in supporting relation to the door, but permitting of non-binding swinging thereof.

The crosshead 9 is formed with an axial bore 14 therethrough, and plungers 15 are slidably disposed in the bore 14 in axial alignment; adjacent ends of said plungers being socketed, and a compression spring S being seated in said sockets and extending between the plungers, whereby to simultaneously urge the same axially outwardly in opposite directions.

At their outer ends the plungers 15 are fitted with non-friction rollers 16 which constantly ride on a horizontal elliptical track 17 formed internally in the case 7 on the sidewalls thereof, and being continuous. This elliptical track 17 is disposed with its major axis parallel to the door in its closed position.

The elliptical track 17 is formed with roller receiving depressions or notches disposed 90° apart, with one pair 18 in alignment parallel to the closed position of the door, and another pair 19 in alignment parallel to the open position of the door.

By reason of the spring pressure on the plungers 15, and the elliptical configuration of the track 17, said spring pressed plungers normally tend to assume the position shown in full lines in Fig. 2, so as to maintain the door 3 in closed position. Thus, the rollers 16 normally but releasably seat in the notches 18.

With the described arrangement the door can be swung in either direction with ease; the door control mechanism thereafter functioning positively but smoothly and easily to return the door to closed position, unless the door is swung open sufficient that the rollers 16 engage in the notches 19. When the rollers engage in said notches 19, the door is releasably held in open position in one direction or the other.

While the swing door control mechanism is here shown as embodied in a floor socket, it could

of course be at the top of the door and socketed into the header.

At the end of the door opposite the described control mechanism (here, at the top of the door), the latter is pivoted in alignment with the spindle 10 by means of another spindle 20 mounted on the door and running in a bearing plate 21 in the adjacent portion of the door frame. The spindle 20 includes a crosshead 22 threaded on an adjustment screw 23, turnably but axially immovably carried in an angle plate 24 fixed to the adjacent door corner. By reason of this adjustment the spindle 20 can be aligned with the spindle 10 for proper swinging of the door 3.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful, and upon which Letters Patent are desired:

A control mechanism for a swing door comprising, a vertical spindle adapted to be non-turnably connected to and project from one horizontal edge of the door, a case having a horizontal elliptical track formed therein, said case being adapted to be secured on a fixed structure

adjacent but vertically spaced from said edge of the door, and so that the axis of the spindle is disposed centrally of the track, an enlarged head on the spindle within the case, the latter including a cover plate through which the spindle projects in turnably guided relation, the head having a bore extending therethrough diametrically of the spindle, plungers slideable in the bore and having track engaging elements on their outer end, the plungers having sockets open to their inner end, and a compression spring in the sockets extending between and bearing against the bottom thereof.

ROBERT G. POLSON.
